ICE CREAM SERVER

Bede Stanislaus Nugent, Surry Hills, near Sydney,
New South Wales, Australia

Application February 3, 1950, Serial No. 7,727

Term of patent 14 years

(Cl. D44—29)

To all whom it may concern:

Be it known that I, Bede Stanislaus Nugent, a subject of the King of Great Britain, and resident of 379 Riley Street, Surry Hills, near Sydney, in the State of New South Wales, Commonwealth of Australia, have invented a new, original, and ornamental Design for Ice Cream Server, of which the following is a specification, reference being had to the accompanying drawing, forming part thereof:

Fig. 1 is a side elevational view of an ice cream server, showing my new design;

Fig. 2 is a top plan view;

Fig. 3 is an end view taken from the right of Fig. 2; and

Fig. 4 is a sectional view taken on line 4—4 of Fig. 1.

I claim:

The ornamental design for an ice cream server, as shown.

BEDE STANISLAUS NUGENT.
